UNITED STATES PATENT OFFICE

138,030

DESIGN FOR A COMBINED TOOTH POWDER AND TOOTHBRUSH CASE

James E. Mathews, Albuquerque, N. Mex.

Application January 27, 1944, Serial No. 112,350

Term of patent 7 years

(Cl. D86—10)

To all whom it may concern:

Be it known that I, James E. Mathews, a citizen of the United States, residing at Albuquerque, in the county of Bernalillo and State of New Mexico, have invented a new, original, and ornamental Design for a Combined Tooth Powder and Toothbrush Case, of which the following is a specification, reference being had to the accompanying drawing, forming part thereof.

Figure 1 is a side elevational view of a combined tooth powder and toothbrush case showing my new design, the top thereof being illustrated in open position, and the discharge end being in closed position.

Figure 2 is a view similar to Figure 1 showing the case in closed position and the discharge end closed.

Figure 3 is an elevational view of the opposite side of the case, and showing the top and discharge end in closed position.

Figure 4 is a view similar to Figure 3 but showing the powder discharge end in open position, and the top in closed position.

I claim:

The ornamental design for a combined tooth powder and toothbrush case, as shown.

JAMES E. MATHEWS.
